UNITED STATES PATENT OFFICE

2,539,488

ELECTROACOUSTIC DIAPHRAGM COUPLING

Dennis Edward Skelton, London, England, assignor to International Standard Electric Corporation, New York, N. Y.

Application October 22, 1946, Serial No. 704,965
In Great Britain August 27, 1945

Section 1, Public Law 690, August 8, 1946
Patent expires August 27, 1965

5 Claims. (Cl. 179—181)

1

This invention relates to electro-acoustic devices and particularly to the method of coupling parts of the moving systems of such devices.

One object of the invention is to increase the allowable tolerances in manufacturing such a device.

Another object of the invention is to provide a method of coupling two co-operating parts of the moving system such that the electro-acoustic device will operate with substantially unimpaired efficiency when the relative rest positions of the two parts are changed.

One feature of the present invention comprises an electro-acoustic device in which two co-operating parts of the moving system are so formed that contacting portions of the parts are stiff in the direction of movement, that there is flexibility between the contacting portions normal to the direction of movement, and that the static pressure exerted between the two portions for a range of relative positions varies to such a small extent that the steady deflection, and consequently the stiffness, of the moving system does not vary substantially over said range.

A second feature of the invention comprises an electro-acoustic device in which two co-operating parts of the moving system are so formed as to be capable of adjusting themselves to a range of relative positions without substantial distortion of either part from its free rest position and without consequent substantial variation of the stiffness of the moving system.

The two parts of the moving system will usually be a diaphragm and a front electrode but might also, for instance, be two parts of a compound diaphragm.

The invention is accomplished by forming flexible serrations in the edges of a center aperture, or in the outer periphery, of one of the members in a direction substantially parallel to the direction of movement of the two members. The serrated portion of this member is fitted against substantially parallel portions of the other member so that the serrations exert a pressure against the second member in directions normal to the direction of movement of the two members.

Various possible embodiments of the invention are illustrated in the accompanying drawings in which—

Fig. 1 shows in cross-sectional side elevation, the present preferred embodiment of the invention comprising the movable electrode and diaphragm of a carbon-granule telephone transmitter.

2

Figs. 2-7 show alternative constructions of diaphragms and electrodes.

Referring next to Fig. 1, the electrode 1 has a central domed portion 2, although this might be of any suitable concave form.

The diaphragm 3 is apertured at the centre and formed with a substantially cylindrical central portion 4, the edge of which is serrated to form teeth 5.

10 The diameter of the cylindrical portion 4 is slightly smaller than the diameter of the dome 2, so that the cylindrical portion fits within the dome with the teeth engaging its inner surface.

Ideally the contacting surfaces of the two parts; 15 in this case diaphragm and electrode; would both be parallel to the direction of movement, and so dimensioned that the male member frictionally fits within the female member. The extent to which the male member enters the female 20 member during assembly could then vary in accordance with easy manufacturing limits without varying the pressure between the two members.

The use of two such cylindrical surfaces would 25 however of itself introduce fine manufacturing limits and therefore the contacting surfaces are designed so that they are at a small angle to one another but only vary a few degrees from the true cylindrical form.

Due to the flexibility of the teeth 5 normal to 30 the axis deflection can take place to allow a range of positions of part 4 in the dome 2 with little increase of pressure between the parts. Increase of pressure between the parts increases the stiffness of the mechanical system because in such 35 structures stiffness increases rapidly with deflection on account of the tensions introduced in addition to the bending stresses which control the stiffness when the deflection is very small. Increase of stiffness resulting from deflection is 40 undesired because it is difficult to control, and in the present construction this is avoided because due to the flexibility of the teeth 5 normal to the axis part 4 may have a range of positions 45 in dome 2 without appreciable pressure in the axial direction or appreciable deflection of either part from its free rest position.

This eases the axial limits necessary in the manufacturing the contacting members. A degree of manufacturing tolerance is also possible in the circular form of the teeth 5 and the dome 2, and in the concentricity of these parts or of the diaphragm and electrode seatings.

The two vibratable members, diaphragm and 50 electrode should be coupled together in such a

manner that they vibrate substantially in phase as one piece. This will be achieved when the mechanical reactance of the coupling member (e. g. teeth) is large (of the order of 5 times as great) compared with the mechanical impedance on either side of the coupling.

The contacting surfaces should be as near to parallelism with the direction of movement as will permit of ease of manufacture, but, of course, the absolute and relative slopes of the contacting surfaces can vary so long as there would be no appreciable relative vibration of the parts coupled.

The contact between the surfaces is such that relative motion takes place when the forces caused by deflection in the direction of drive exceeds the static friction which is determined by the nature of the surfaces, the angle of the surfaces to the direction of drive, the angle between the surfaces, and the component force between the surfaces normal to the direction of drive. Such relative motion will take place when the deflection of either part from its individual rest position reaches a value of the order of 1 . . . 5 mils in the embodiment described, and the absolute deflection that can occur is thereby limited. The desired vibratil deflections of the two parts moving as one have an amplitude of a fraction of a mil and for such amplitudes no relative motion or slipping will take place.

It will be seen that such an arrangement not only allows of easy manufacturing limits but is also capable of taking up changes in the relative static positions of the two parts due to variations in pressure differences between the air chambers on opposite sides of the diaphragm and electrode respectively; for instance the variations likely to be encountered when the electrode chamber is effectively sealed.

While the facility of relative movement of the surfaces after assembly is useful in certain conditions, these conditions are not universally required to be met in the design of electro-acoustic devices. When the facility is not required, it may be desirable to put cement of a liquid or semi-liquid kind which subsequently sets hard between the contacting surfaces during assembly so that when the parts have taken up their optimum relative positions, the compound will unite the contacting surfaces permanently.

In Fig. 1, such an operation will stick the teeth 5 to the interior of the dome 2 from tip to root thus eliminating an acoustic leak between the front and back of the diaphragm during vibration at acoustic frequencies and preventing passage of breath moisture.

It may be preferred to use viscous compounds which will allow of slow adjustment of relative positions; such compounds will readily transmit vibrations at acoustic frequencies. The use of a viscous compound in place of cement permits satisfactory operation with less pressure between the contacting surfaces in a direction normal to the direction of drive and thereby allows the device to operate with a smaller limiting deflection than the 1 . . . 5 mils mentioned above.

In Fig. 2, the electrode is in two parts, a flexible base member 1 having a truncated conical central portion 2 into which the toothed cylinder 4, 5 of the diaphragm 3 fits. The active portion of the electrode is formed by a dome 6, preferably of carbonized nickel.

In Fig. 3 the truncated conical portion 2 of the electrode of Fig. 2 is formed on the front side of the electrode instead of the back and the

members 2, 4 have opposite slopes relative to the axis. The teeth in this case are on the part 2 of the electrode instead of on the diaphragm. As in Fig. 2, the electrode is compound, the active surface being provided by a dome-shaped member 6 preferably of carbonised nickel.

In the arrangement of Fig. 4, the diaphragm is similar to that in Figs. 1 and 2, but the electrode is compound, comprising a disc 1 centrally apertured to receive a thimble 6 having a domed active surface and an extension 2 in front of the disc 1 to provide an extended interior surface of constant slope for contact with the teeth 5.

The arrangement of Fig. 5 is similar to that of Fig. 3, the difference being that the teeth are on the diaphragm instead of on the electrode and the teeth are exterior to the reversely-sloped part 2 of the electrode.

In Fig. 6, the invention is applied, not between diaphragm and electrode, but between two parts of a compound diaphragm. The outer part 7 of the diaphragm comprises an annulus 7 with a truncated conical internal extension within which bears a substantially cylindrical ring of teeth 5 on a conical portion 3. The conical portion is centrally apertured and formed with a lip 4 having a smaller angle to the axis and bearing on the base of the dome 2 of electrode 1.

In Fig. 7, the invention is again applied between the diaphragm and electrode. The diaphragm 3 has a central truncated-conical extension 4 without teeth. The compound electrode comprises a disc 1 and a domed member 6, from the base flange 8 of which are cut a series of teeth. Alternate teeth 9 are used in conjunction with the flange 8 for fixing the domed member 6 to disc 1. The unbent alternate teeth 5 make contact with the exterior of the diaphragm extension 4.

In the embodiments described only one of the contacting members has had flexibility normal to the direction of movement. It is within the scope of the invention that both contacting members should contribute to such flexibility.

What is claimed is:

1. An electro-acoustic diaphragm comprising an electrode, a diaphragm, said electrode and said diaphragm both movable in the same direction, a portion of said electrode overlying a portion of said diaphragm, said electrode and said diaphragm each having a portion extending substantially parallel to the said direction of movement, said diaphragm having a plurality of serrations around an edge of its extended portion, said serrations engaging a portion of the inner surface of the extended portion of said electrode permitting maximum friction between said diaphragm and said electrode in a direction parallel to the direction of movement thereof and maximum resilience between said diaphragm and said electrode in a plane normal to the direction of movement thereof.

2. An electro-acoustic diaphragm comprising an electrode, a diaphragm, said electrode and said diaphragm both movable in the same direction, a portion of said diaphragm overlying a portion of said electrode, said diaphragm and said electrode each having a portion extending substantially parallel to the said direction of movement, said electrode having a plurality of serrations around an edge of its extended portion, said serrations engaging a portion of the inner surface of the said extended portion of said diaphragm, permitting maximum friction between said diaphragm and said electrode in a direction parallel

to the direction of movement thereof and maximum resilience between said diaphragm and said electrode in a plane normal to the direction of movement thereof.

3. An electro-acoustic transducer that comprises a substantially conical diaphragm having its apex facing inwardly, means for supporting said diaphragm around its outer margin in a manner permitting substantially free axial motion, an otherwise flat diaphragm having a dome-like formation near the center thereof mounted at its margin and arranged relative to the conical diaphragm in a manner such that it can move in a direction common to the motion of the conical diaphragm, said diaphragms being disposed so that apex portions of the frusto-conical diaphragm are within and arranged coaxially relative to the dome formation of the otherwise flat diaphragm, the improvements that comprise means for coupling the frusto-conical diaphragm and the diaphragm having the dome formation whereby the diaphragms move in unison and are rigidly coupled for motion along the axis of the frusto-conical diaphragm but are flexibly coupled for motion normal to such axis, said coupling means comprising a plurality of flexible elements formed on marginal portions of the frusto-conical diaphragm near its apex engaging with the inside of the dome-like formation of the

otherwise flat diaphragm for transmitting motion thereto.

4. An electro-acoustic transducer as defined in claim 3, further characterized in that the flexible elements constituting the coupling means are serrations formed on the edge of the frusto-conical diaphragm frictionally engaging with and fitting closely against inner portions of the dome-like formation of the otherwise flat diaphragm.
5. An electro-acoustic transducer as defined in claim 3, further characterized in that the flexible elements constituting the coupling means are serrations formed on the edge of the frusto-conical diaphragm, adhesively attached at their end portions to inner portions of the dome-like formation of the otherwise flat diaphragm.
